CLAIM

An ornamental design for a bath faucet filter as shown and described.

DESCRIPTION

FIG. 1 is an illustration of a top perspective view of a bath faucet filter.

FIG. 2 is an illustration of a front view thereof;

FIG. 3 is an illustration of a rear view thereof;

FIG. 4 is an illustration of a left side view thereof;

FIG. 5 is an illustration of a right side view thereof;

FIG. 6 is an illustration of a top view thereof;

FIG. 7 is an illustration of a bottom view thereof; and,

FIG. 8 is an illustration of a top perspective view of a bath faucet filter, according to another embodiment.

The texture lines and broken lines of the bath faucet filter and the universal bath faucet connector are for the purpose of illustrating portions of the bath faucet filter and the universal bath faucet connector along with an unclaimed water faucet and form no part of the claimed designs.
